UNITED STATES PATENT OFFICE.

ARTHUR H. WOLFE, OF PHILADELPHIA, PENNSYLVANIA, ASSIGNOR OF ONE-HALF
TO DURWARD A. WOLFE, OF GRAND RAPIDS, MICHIGAN.

FOLDABLE ARTICLE CASE.

Application filed July 10, 1924. Serial No. 725,274.

To all whom it may concern:

Be it known that I, ARTHUR H. WOLFE, a citizen of the United States, residing at W. Philadelphia, in the county of Philadelphia and State of Pennsylvania, have invented certain new and useful Improvements in Foldable Article Cases; and I do declare the following to be a full, clear, and exact description of the invention, such as will enable others skilled in the art to which it appertains to make and use the same.

My invention relates to improvements in foldable cases for containing numerous articles, such as cigarettes, matches, playing cards, visiting cards, stamps, and a myriad of others.

The principal object of the invention is to provide an extremely simple and inexpensive device of the type set forth, in which an article container is mounted in a unique manner, in a comparatively flat casing having an open side, said container being movable through said open side of the casing, 25 to a position at an angle to the latter, whenever desired, so that the casing contents may be readily accessible.

In carrying out the above end, a further aim is to provide a structure in which the article container may recline toward one wall of the casing when said container is swung outwardly, thus providing for holding the container in an extended position for use, when the casing rests on any substantially horizontal support.

Another object of the invention is to provide a sheath for the article container, said sheath being normally within the casing and retaining the container in the latter, 40 said container however being outwardly movable from the sheath, when said sheath and container are bodily extended from the casing.

In providing for the desired movements of the container, or the sheath and the container as the case may be, an arrangement of tracks and shoes is provided, the tracks being disposed at opposed walls of the casing, and the shoes being slidably engaged 50 with said tracks, a further object of the invention being to provide an improved track-forming structure which will not only

impart an attractive appearance to the edges of the casing, but will shield the 55 shoes.

Yet another object is to provide a novel container for a box of safety matches, said container being provided with an inwardly stamped flange which engages one side of the match box to hold the latter against 60 movement in one direction, the inward stamping of said flange also providing a slot through one side of the container, through which matches may be inserted, when it is desired to strike them upon the 65 box.

A still further object is to provide a simple, light and compact foldable case which may be readily carried within the user's pocket, without danger of injuring 70 the pocket lining.

With the foregoing and minor objects in view, the invention resides in the novel subject matter hereinafter described and claimed, the description being supplemented 75 by the accompanying drawings.

Figure 1 is a perspective view showing one form of the pocket case in its closed position.

Figure 2 is a view similar to Fig. 1 but 80 partly in section, showing the sheath and the article container swung out of the casing and also showing said article container swung out of the sheath.

Figure 3 is a perspective view of the casing shown in Figs. 1 and 2.

Figure 4 is a perspective view of the article container.

Figure 5 is a perspective view of the sheath.

Figure 6 is a vertical sectional view taken substantially on line 6—6 of Fig. 2.

Figure 7 is a vertical section on line 7—7 of Fig. 3.

Figure 8 is a horizontal sectional view 95 on line 8—8 of Fig. 6.

Figure 9 is an enlarged horizontal sectional view on line 9—9 of Fig. 4.

Figure 10 is a vertical section on line 10—10 of Fig. 6.

Figure 11 is a perspective view showing a different form of article container which is mounted directly within the outer casing instead of being confined within a sheath.

Figure 12 is a perspective view showing a modified form of outer casing.

Figure 13 is a perspective view showing a greatly simplified casing which may in some instances be preferable.

I will first describe the form of construction illustrated in Figs. 1 to 10, which construction comprises briefly, an outer substantially flat casing 1 having an open side, 10 a sheath 2 normally confined within the casing and also having at least one open side, and an article container 3 within the sheath and movable outwardly through the open side thereof when said sheath and container 15 are swung outwardly from the casing (see Fig. 2).

The casing 1, in the construction under consideration, comprises a flat bottom plate 4, a front wall 5 rising therefrom, a back wall 6, and a pair of opposed side walls 7. The bottom plate 4 and all of the walls 5, 6 and 7 are preferably formed from a single piece of sheet metal, such as aluminum, and when the walls 7 are stamped, they are 20 formed about twice as wide as the front and back walls 5 and 6, so that said side walls may have their upper portions bent inwardly and downwardly to provide flat vertical flanges 8 at the inner sides of the side walls 25 proper; the latter being preferably bowed outwardly away from the flanges as seen for instance in Figs. 2, 3, 6 and 7. The front and back walls 5 and 6 are also by preference bowed transversely as shown, so that a 30 rounded formation is provided at all edges of the casing, giving an attractive appearance and overcoming danger of any sharp edges injuring the lining of the user's pocket, when the device is being carried therein.

40 At their rear ends, the flanges 8 are formed with longitudinal slots 9 constituting tracks for a purpose to appear, said tracks being short with respect to the length of the walls 7. Entrance throats 10 are 45 formed into the slots 9 and the function of these throats will be also described herein-after.

The sheath 2 is of substantially U-shaped form, being provided with two parallel flat 50 side plates 11 and with a transversely curved front wall 12. This sheath is also preferably provided with a flat side wall 13 joined to the plates 11 and wall 12, said side wall 13 however having a rather large opening 55 14 for a purpose to appear, while the side plates 11 are preferably formed with arcuate slots 15 whose function will also be described later.

The article container 3 is received within 60 the sheath 2 and it may be of any desired construction. It is preferably provided however with an open top and a closed bottom, and is equipped with a pair of ears 16 projecting beyond said bottom for disposition at the free ends of the side plates 11.

A rod 17 passes through openings in the ears 16 and the above-named free ends of the side plates 11, and the ends of this rod project slightly beyond said side plates and are provided with any appropriate flat heads 70 18. The projecting portions of the rod 17 and the heads 18 are downwardly insertible through the throats 10 of the casing 1, so that said portions of the rod will be received in the slots or tracks 9 and will constitute shoes which may slide along said tracks.

The wall 12 of the sheath 2 is provided with a knob 19 having a shank 20 receivable in a slot 21 formed in the free edge of the 80 front wall 5 of the outer casing 1, so that by pushing upwardly upon this knob, the sheath 2 and container 3 may be swung upwardly, the rod 17 then forming a pivot. When this pivotal action takes place, the 85 rod is at the rear ends of the tracks 9, but after such swinging has been accomplished, the rod may be slid forwardly within the tracks, so that the sheath 2 may recline toward the back wall 6 of the casing, as illustrated in Fig. 2. The container 3 may then be swung forwardly to give access to its contents, and to limit the outward swinging of said container, it is provided with lugs 22 operable within the arcuate slots 95 15 of the sheath 2.

The article container 3 is preferably constructed from a single piece of sheet aluminum and this holds true also of the sheath 2. The container in question, in the construction shown, comprises a front plate 23 having rearwardly bent flanges 24 at its vertical edges, and a back plate 25 having forwardly bent flanges 26 at its vertical edges, the front edges of the flanges 26 105 being bent inwardly against the outer side of the front plate 23, as indicated at 27, while the two sets of flanges are in contact with each other to provide vertical end walls for the container, as shown most clearly in Figs. 8 and 9.

The front and back walls 23 and 25 are bent upwardly from a bottom 28 and the upper edge of said front wall is preferably notched as at 29 to give access to cigarettes 115 30 and safety matches 31 which may be carried in the container, the cigarettes being left within a portion 32 of an ordinary cigarette package, while the matches remain in the usual safety match box 33, an appropriate support 34 being provided in the container 3 to support the drawer or inner section of the match box extended above the outer section or sleeve, as seen in a number of the views, said support 34 being shown only in dotted lines in Fig. 10.

The package 32 and the match box 33 are adapted to abut each other at their inner edges, and the outer edge of the match box 120 engages a flange 35 which is stamped in

wardly from the front wall 23 of the article container 3, the inward stamping of said flange also forming a vertical slot 36 in the wall 23. Through this slot, the headed end 5 of a match may be inserted, as illustrated in Fig. 8, so that said match may be struck upon the box 33. Preferably, a portion of one of the inwardly bent edges 27 is bent further at one edge of the slot 36 as shown 10 at 37 in Figs. 8 and 9.

I have previously mentioned an opening 14 in the side wall 13 of the sheath 2. This opening is to permit the user's fingers to engage the rear side of the container 3 when 15 it is swung outwardly with the sheath 2, whereby said container may be forced forwardly as indicated in Fig. 2, giving easy access to the cigarettes 30 and matches 31, or to any other articles which may be contained 20 within the device.

In Fig. 11, an article container 3^a is shown provided with shoes 18^a which are adapted to engage the tracks of a suitable outer casing, such as that above described, or one of 25 those to be hereinafter described. This form of container is not used with a sheath such as that above described, and it is provided with an angular flange 38 at its open upper end adapted to hook over the front wall of 30 the outer casing, when the container is closed within the casing. The intermediate portion of the flange 38 may well be outwardly bowed to some extent as indicated at 39, so that the user's thumb may be readily engaged 35 with it to open said container when desired. A container of this general type may be constructed to carry any desired articles, cigarettes and matches being shown within it, accessible through openings 40 and 40 41, respectively. An opening 42 is also shown giving access to the usual striking surface of the match holder, it being understood that the matches shown are of the cardboard variety, stamped from sheets 45 which are secured together and bound at one end.

In Fig. 12, a casing structure is shown which differs from that previously described, in that only the intermediate longitudinal portions of the side walls 7^a are transversely bulged, as indicated at 43. These walls are provided with downwardly 50 projecting flanges 8^a and with slots 9^a, and the casing is used in the same manner as above set forth.

A still further simplified casing structure is shown in Fig. 13, in which the opposed side walls 7^b of the casing are of one-ply construction and are strictly flat, track-forming slots 9^b being formed through said walls. Any desired form of article container or article container and sheath, may be used in connection with the casings shown 55 in Figs. 12 and 13, and I wish to here further state that my invention is not restricted

to any particular type of article container, as the construction of such container may vary a great deal according to the uses for which it is adapted. It may be further stated that within the scope of the invention as claimed, numerous modifications may be made with regard to other features of the invention. 70

It will be seen from the foregoing that a simple, inexpensive and desirable device 75 has been provided to carry out the objects of the invention, and while excellent results have been obtained from the general construction shown, other constructions may be followed if desired, as above stated. 80

I claim:

1. A device of the class described comprising a substantially flat casing open at one side and having short longitudinal tracks along opposed walls, said tracks being disposed only at one end of the walls, and a movable member received normally within said casing and having shoes slidably engaged with said track, said shoes being normally disposed at the outer ends of the tracks and permitting outward swinging of the movable member from the casing, while sliding of said shoes toward the inner ends of the tracks permits the movable member to recline toward one wall of the casing. 95

2. A device of the class described comprising a substantially flat casing open at one side and having short longitudinal tracks along opposed walls, said tracks being disposed only at one end of the walls, a sheath 100 normally within said casing and having an open side, said sheath being provided with shoes slidably engaged with said tracks, said shoes being normally disposed at the outer ends of the tracks and permitting outward swinging of the sheath from the casing, while sliding of said shoes toward the inner ends of the tracks allows the sheath to recline toward one wall of the casing, and an article container movably mounted in said sheath and adapted for movement through the open side thereof when said sheath is in its reclining position. 110

3. A device of the class described comprising a substantially flat casing having an open side, opposed walls of said casing being provided with longitudinal tracks, a sheath disposed normally within said casing and having an open side normally disposed adjacent the closed side of the casing, said sheath being provided with shoes engaging said tracks to permit outward swinging of the sheath and sliding thereof with respect to the casing, and an article container movably mounted within said sheath and adapted for movement through the open side thereof after the sheath is swung outwardly. 115 120 125

4. A structure as specified in claim 3; said article container being pivotally mounted in the sheath by means of a rod passing 130

through portions of said container and sheath, the ends of said rod forming the aforesaid shoes.

5. A structure as specified in claim 3; 6. A structure as specified in claim 3; said sheath having an opening in the side thereof opposite its open side, for the purpose set forth.

6. A device of the class described comprising a substantially flat casing having an open side, opposed walls of said casing having flanges bent inwardly and toward the closed side of the casing, said opposed walls being transversely bowed away from said flanges and the latter being formed with longitudinal slots, and a movable member normally

within said casing, said member having shoes projecting outwardly through the aforesaid slots.

7. A device of the class described comprising a container open at one end to receive 20 a match box, a portion of the front wall of said container being stamped inwardly to provide a flange for engaging one edge of the match box and to also form a slot 25 through which the headed ends of matches may be inserted for striking on the box.

In testimony whereof I have hereunto affixed my signature.

ARTHUR H. WOLFE.
